(57) **CLAIM**

The ornamental design for a sampling mitt as shown and described.

DESCRIPTION

FIG. 1 is a perspective view of a sampling mitt showing our new design;

FIG. 2 is a top side view of the sampling mitt of FIG. 1, which is identical to the bottom side view; and,

FIG. 3 is an elevational left side view of the sampling mitt of FIG. 1, which is identical to the elevational right side, front side and rear side views.

The short dashed bolded lines depict weld regions between the top side and bottom side that include one or more weld lines that appear as slight indentations in the top and bottom surfaces.
